ADJUSTABLE SUPPORT

Filed June 22, 1927

Fig. 1

Robert T. Frost Inventor

UNITED STATES PATENT OFFICE

ROBERT T. FROST, OF OAKLAND, CALIFORNIA

ADJUSTABLE SUPPORT

Application filed June 22, 1927. Serial No. 200,606.

My invention relates to an adjustable support particularly designed for the support of clothing and the like.

An object of the invention is to provide a support of the character described whereby clothing on hangers may be disposed overhead and out of the way and yet may be readily accessible.

Another object of the invention is to provide a means for utilizing space for the storage of clothing and the like which is now unused as a storage space.

The invention possesses other objects and features of advantage, some of which, with the foregoing, will be set forth in the following description of the preferred form of the invention which is illustrated in the drawings accompanying and forming part of this specification. It is to be understood, however, that I do not limit myself to the showing made by the said drawings and description, as I may adopt variations of the preferred form within the scope of my invention as set forth in the claim.

Referring to said drawings:

Figure 1 is a perspective view showing two of the devices mounted in a clothes closet and differently disposed.

Figures 2 and 3 are side and front views, respectively, of a bracket and the lower portion of a standard forming parts of the device.

Figure 4 is a view taken on the line 4—4 in Figure 3.

Figure 5 is a view taken on the line 5—5 in Figure 4; and

Figure 6 is a view generally similar to Figure 5, but with an arm forming part of the bracket disposed as shown in dotted lines in Figure 2.

As herewith particularly illustrated, the support of my invention comprises a standard 7 vertically and adjustably supported in a wall bracket 8. The standard 7 is preferably formed of a straight bar of polygonal section, here shown square, and is provided at its upper end with a transversely extending arm 9 arranged to be horizontally disposed and to provide a support for a plurality of clothes hangers 11, or the like, which are arranged to be removably hung thereon. To

insure the retention of the hangers on the arm, the latter is preferably provided with an upward extension 12 at the extremity thereof. The standard and arm may be advantageously formed as integral parts of a single member, though such is not essential to the operativeness of the device.

While the bracket 8 may be of other structure, I prefer to form the same as shown, since the present structure, besides being particularly simple, involves a minimum of manipulation during an adjustable shifting of the position of the standard therein. The bracket 8, it is noted, essentially comprises a back or base portion 13 arranged to be secured to and against a wall by screws or the like, while extending transversely forwardly from the portion 13 at the top and bottom thereof are arm portions 14 and 15, respectively, one of said portions being fixed to the base and disposed horizontally, while the other of said portions is hinged to the base for limited movement about a horizontal axis. The upper arm 14 is fixed and is integral with the back portion 13, such portion being conveniently formed of a strip of sheet metal. The lower arm 15, it will be noted, is also formed of a strip of sheet metal, and is provided adjacent the opposite edges thereof with tongue portions 16, which are disposed through horizontally disposed aligned slots 17 provided adjacent the bottom of the base 13 with the extending portions bent transversely of the plane of the arm. A portion 18 of the strip forming the arm 15 and which lies between the tongues 16 is also bent transversely of the plane of the arm, but oppositely of the tongues and in front of the base. It will now be noted that the arm 15 is arranged to be disposed generally horizontally and that the tongues 16 thereof extend downwardly while the portion 18 extends upwardly at right-angles thereto, whereby the arm is hingedly secured to the base and the upward movement thereof is limited to a position at right-angles to the base and parallel to the fixed arm 14.

The arms 14 and 15 are respectively provided with perforations 19 and 21, such perforations being substantially vertically 100

aligned when the arms are parallelly disposed and being arranged to slidably receive the standard 7 therethrough. Preferably, the perforations 19 and 21 are of the same shape as the section of the standard whereby rotation of the latter is preferably prevented. The perforation 21 is slightly larger than the perforation 19 whereby the arm may assume an oblique relation to the standard with the lower forward edge portion 22 of the perforation engaging the outer side of the standard while the upper rear edge portion 23 of the perforation engages the inner side of the standard. In this manner, a downward gravitational movement of the standard and arm 15 locks them together, it being noted that the edge portions 22 and 23 are preferably relatively sharp and that the standard is arranged to be vertically disposed when so engaged with arm 15. To facilitate a proper locked engagement of the standard and arm 15, the standard is preferably arranged to be so engaged in the arms that an edge thereof is furthest from the bracket base, with the faces coterminous at such edge making equal angles with the plane of the bracket base, it being noted that such a relation insures a maximum length of engagement of the standard with the edges of the perforation of the arm 15.

To raise the standard, it is merely necessary to push upwardly thereon to release it and move it upwardly to a new position. If it is desired to lower the standard, it is only necessary to raise it sufficiently to free the arm 15 therefrom, and then hold arm 15 in substantially horizontal position while lowering the standard therethrough. In either case, if the arm 15 is free to move, a slight downward movement of the standard serves to lock it in place; it is thus clear that adjustment of the positioning of the standard is effected in a particularly simple manner. Preferably, and as here shown, a push knob 24 providing a downwardly convex bearing surface is provided at the lower end of the standard 7 to facilitate the manipulation thereof.

It will be noted that the device of my invention is particularly intended for disposing clothing out of the way and in space usually wasted. Thus, as particularly shown in Figure 1, the device may be mounted on a hook strip 25 on a wall 26 of a clothes closet. With the standard in lowered position to dispose the arm 9 substantially at the level of the hooks 28, one or more hangers 11 carrying clothing 29 may be mounted thereon, after which the standard is raised to dispose the hangers adjacent the ceiling 31 with the clothing above the hooks 28, thus utilizing space usually wasted in clothes closets and leaving the hooks free for other use.

From the foregoing description taken in connection with the accompanying drawings,

the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made, when desired, as fall within the scope of the appended claim. 70 75

Having thus described my invention, I claim as new and desire to secure by Letters Patent of the United States, the following:

In a clothes support, a standard comprising a bar of polygonal cross-section provided at one end thereof with a clothing supporting arm extending transversely of the standard, a wall bracket for supporting said standard and comprising a base portion arranged to be secured to a wall and arms extending outwardly from said base portion, said arms provided with openings arranged to be vertically aligned for the cooperative sliding reception of said standard therein, one of said arms being of the same cross-sectional shape as said bar to prevent the turning of the bar therein, one of said arms being fixedly related to the base portion and the other arm being hinged to said base portion to gravitationally support the standard where desired. 33 90 95

In testimony whereof, I affix my signature.
ROBERT T. FROST.
